UNITED STATES PATENT OFFICE.

CHARLES L. E. REBERT, OF LOS ANGELES, CALIFORNIA.

DETACHABLE SHIRT-CUFF.

1,270,660.

Specification of Letters Patent. Patented June 25, 1918.

Application filed June 25, 1917. Serial No. 176,861.

To all whom it may concern:

Be it known that I, CHARLES L. E. REBERT, a citizen of the United States, residing at Los Angeles, in the county of Los Angeles, 5 State of California, have invented new and useful Improvements in Detachable Shirt-Cuffs, of which the following is a specification.

My invention has relation more particularly to a detachable soft cuff for attachment to the sleeves of various styles of shirts, and especially that class of shirts worn by men and known as "soft shirts."

An object of my invention is to provide 10 a novel form of folded soft cuff formed from suitable materials which may be detachably secured to the sleeves of shirts or similar garments.

A further object of my invention is to 15 provide a detachable cuff which may be reversed when one side becomes soiled or worn.

I accomplish the above recited objects by 20 means of the construction described herein and illustrated in the accompanying drawings, in which:

Figure 1 is a side view of a portion of a shirt sleeve having my improved cuff attached thereto.

Fig. 2 is a perspective view of a portion 25 of my improved detachable and reversible cuff.

Fig. 3 is a perspective view of the lower end of a shirt sleeve, showing the cuff securing means.

Fig. 4 is a face view of my detachable 30 and reversible cuff, parts being broken away.

Fig. 5 is a face view of a modified form of cuff.

Fig. 6 is a perspective view of another 35 modified form of cuff.

Heretofore soft shirts have been constructed from various fabrics, such as linen, silk, cotton or other materials, having double fold cuffs generally formed integrally with each sleeve. While such a construction has proven satisfactory in a large measure, yet by reason of the fact that the cuffs are the most exposed parts of a shirt they become quickly soiled and as they are also subject to undue wear, they have proven more or less expensive to the wearer.

By means of my improved form of detachable and reversible cuffs the above mentioned unsatisfactory conditions have been largely eliminated. My form of cuffs wear

longer and also increase the length of time a shirt may be worn.

Referring more specifically to the drawing, 5 designates a portion of a shirt sleeve. 60 To the wrist band 6 is secured, in any suitable manner, a button, or other securing means 6'. Referring more particularly to Fig. 2 the body of cuff 7 is formed from any suitable soft material, preferably of the 65 same material as the shirt with which it is intended to be worn, and is preferably formed of two pieces of fabric —b— and —c— stitched together along its edges, and a stiffening material (not shown) may be 70 inserted between the cuff pieces —b— and —c— if desired.

Formed at approximately the center between the fold and the edges of body 7 are button holes 8, said button holes registering when the cuff is folded on the dotted line 9; the ends of the cuffs being secured together by means of cuff buttons —a—. Formed in the two cuff pieces —b— and —c— and preferably at the center thereof 80 adjacent to each of its upper and lower longitudinal edges 10, 11, are concealed button holes 12 and 13 adapted to engage with the button or other securing means 6' on the wrist band 6 of the shirt sleeve, and securely 85 holds the same in engagement therewith. Button hole 12 is formed in cuff piece —b— while button hole 13 is formed in piece —c—, as clearly shown in Fig. 4 of the drawings, so that when the cuff is folded upon itself 90 along line 9, the securing means 6' will be concealed from view, and the cuff will have the appearance of a cuff formed integral with the shirt sleeve.

Wrist band 6 is also provided with button 95 holes 17 and 18 which register when the ends are brought together, and the cuff buttons —a— passing through the button holes 17 and 18 formed therein, and the button holes 8—8 of the cuff, thus securely maintaining 100 the cuff in position on the wrist band of the shirt and presenting the same appearance as a cuff that is formed on a shirt.

When the cuffs of a shirt become soiled (and they quickly do by reason of undue 105 exposure), and it is not desired to change the shirt which is comparatively clean, they are quickly removed and reversed by folding on the median line 9 so as to present a clean and freshly laundered appearance.

In Fig. 5 of the drawings, I have illustrated a modified form of my detachable and

reversible cuff, known to the trade as $\frac{3}{4}$ size, in which the cuff body 7 is of a narrower transverse width than the form shown in Fig. 2. This form is provided with button 5 holes 19, 20 in the corners close to the upper longitudinal edge 21, and button holes 22, 23, said button holes registering when the cuff is folded on the dotted line 26, which line represents a distance of about $\frac{1}{2}$ the 10 transverse width of the cuff. A wrist band button hole 27 is also provided for attachment to the wrist band 6 in the same manner and by similar means as employed and described in connection with the cuff illustrated in Fig. 4. By means of this construction it is only necessary to fold a small portion over in reversing, and only a single wrist band button hole is needed.

In Fig. 6 I have illustrated a form of 20 cuff that is not designed to be folded longitudinally as the other described forms, but is provided with registering button holes 28 and a wrist band button hole 29. This form is secured to the band of the shirt the same 25 as the other forms, and is designed to be preferably used with shirts of a less finer quality than the other forms.

It will be noted from the above description that I have produced an article of great 30 utility as the cuffs may be instantly attached

or detached (from a comparatively clean shirt) by the wearer when soiled and reversed, thus effecting a large saving in laundry. Also, when the cuffs become worn and the shirt is still in good condition, they 35 may be replaced by new ones.

What I claim is:

A detachable and reversible cuff for shirts, the combination of a sleeve of a shirt provided with a waist band having an attaching button secured thereto, a cuff comprising a rectangular body formed of a plurality of pieces of fabric having button holes at approximately each of its corners extending therethrough, and being further provided on 40 its upper and lower longitudinal edges at substantially the center thereof with other button holes, said button holes extending one through one face or ply only and the other through the other face or ply only, and 45 adapted to engage with the cuff attaching means on the wrist band, whereby when the cuff body is folded longitudinally upon itself the cuff can be secured to the sleeve of the shirt and the attaching button concealed 50 from view.

In witness that I claim the foregoing I have hereunto subscribed my name this 27th day of May, 1917.

CHAS. L. E. REBERT.
